ALIDA M. MARCOUX, OF HOPEDALE, MASSACHUSETTS, ASSIGNOR TO DRAPER COMPANY, OF HOPEDALE, MASSACHUSETTS, A CORPORATION OF MAINE.

FILLING-DETECTING MECHANISM FOR LOOMS.

No. 834,585.

Specification of Letters Patent.

Patented Oct. 30, 1906.

Application filed October 28, 1905. Serial No. 284,811.

To all whom it may concern:

Be it known that I, ALIDA M. MARCOUX, a citizen of the United States, and a resident of Hopedale, county of Worcester, State of Massachusetts, have invented an Improvement in Filling-Detecting Mechanism for Looms, of which the following description, in connection with the accompanying drawings, is a specification, like characters on the drawings representing like parts.

This invention relates more particularly to the mechanism in a loom for detecting the presence or absence of the filling as laid by the running shuttle, the detection of filling absence acting automatically to effect a change in the operation of the loom.

My invention has for its particular object the production of novel and simple means for controlling the filling detector or fork, reducing improper vibratory movement thereof to a minimum, and insuring the co-operation of the detector and vibrator or weft-hammer under certain conditions.

I have shown one practical embodiment of my invention in connection with a double-detector loom, as it is particularly adapted for such use; but I do not thereby restrict its application to such type of loom, as it can also be readily employed in single-detector looms.

The various novel features of my invention will be fully described in the subjoined specification and particularly pointed out in the following claims.

Figure 1 is a top plan view, centrally broken out, of a portion of a double-detector automatic filling-replenishing loom with one embodiment of my invention applied thereto. Fig. 2 is a right-hand side elevation of one of the detecting devices with the nearer side of the fork-slide broken out, the fork being shown in position to detect. Fig. 3 is a similar view, but after detection has been effected and the vibrator has moved forward. Fig. 4 is a like view showing the left-hand one of the detectors, Fig. 1, after an initial movement has been given to its slide, as will be explained; and Fig. 5 is a longitudinal sectional view of the hook which is mounted on the vibrator with the fork-controller in elevation.

Referring to Fig. 1, I have shown a portion of automatic filling-replenishing mech-

anism, including a feeder F to hold a supply of filling carriers or bobbins and a trans-ferrer f' to transfer the same one by one to the running shuttle in well-known manner, a rock-shaft d' controlling the operation of said mechanism.

Two filling-detecting devices are shown, 60 designed to normally detect on alternate picks, each device comprehending a filling detector or fork, as f g, a slide for each f' g', and two vibrators or weft-hammers W W', one for each slide, each vibrator having a 65 connected hook w, having a shoulder w' and a rest portion w'', (see Figs. 2 to 5,) formed by its upper edge between the shoulder and the point of the hook. Each hook is longitudinally slotted, as at 1, the ends of the slot 70 being oppositely inclined or flared, as at 2 3, and in the slot a fork-controller is fulcrumed at 4. Said controller is herein shown as an elongated loop-like device 5, adapted to swing in a substantially vertical path in the 75 slot and limited in such movement by the inclined ends 2 3 of the slot. The opening 6 in the controller has an entrance 7, through which the fork-tail is inserted when assembling the parts, the forks f and g, Fig. 1, 80 having tails f'' g'', respectively, of usual construction to cooperate with the hook-shoulders upon detection of filling absence. As the hook in my present invention is slotted the shoulder thereof will be divided or two- 85 part, one part on each side of the slot, as will be manifest, the controller swinging between them. The opening 6 is wide enough to permit easy sliding movement of the fork-tail therein, and when the fork is in detecting po- 90 sition, Fig. 2, its tail acts to hold the controller in practically upright or neutral position, and at such time the controller offers little resistance to tilting movement of the fork.

When the fork is engaged by the filling and is tilted, the tail is lifted, and at the same time the vibrator begins its outward stroke, and thereby the controller is thrown or swung rearward from neutral position 100 and acts upon the fork-tail to depress it onto the rest portion w'' of the hook, as in Fig. 3. The controller thus not only limits the throw of the fork when tilted by the filling, but quickly returns it and maintains it practically 105 quiescent while the vibrator makes the ma-

5 jor part of its outward and return movement. Thereby any improper vibrations or jumps of the fork are prevented and the tail is in position to drop over the shoulder of the hook as the vibrator completes its return stroke, and at such time the combined action of the hook and fork-tail return the controller to neutral position, Fig. 2.

10 When the controller is swung rearward, as in Fig. 3, the end 3 of the slot limits such movement, so that there is no possibility of the controller dropping down too far.

15 I have shown the main or left-hand filling-detecting device in detail in Figs. 2, 3, and 4 to illustrate an additional function of the controller when used on a double-detector loom, such as shown in Fig. 1, and which is substantially the structure forming the subject-matter of United States Patent to Northrop, No. 20 789,291, dated May 9, 1905. In said patent the full outward movement of the main slide f^x acts, through the arm d , to rock the shaft d' far enough to effect the operation of the filling-replenishing mechanism; but when 25 filling absence is detected by the auxiliary fork g its slide g^x , acting through arm d^5 , turns the rock-shaft d' a less distance, but far enough to arrest take-up. Such turning of the rock-shaft, however, causes the upper 30 end d' of arm d to act upon and move outward a latch-carrier 17, Fig. 1, mounted on the main slide, and thereby to impart an initial outward movement to the main slide f^x . This initial movement of the slide with- 35 40 draws the main fork f from the filling path, so that the fork will not be tilted even should a trailing end of filling be present, and thereupon the adjacent hook coöperates with the main fork-tail f^{20} and the slide is moved outward its full distance, causing filling replenishment. In other words, the replenishing mechanism is directly controlled as to its operation by the main fork and indirectly by the auxiliary fork in the manner described.

45 When the initial movement of the main slide is effected, the fork-tail acts upon the controller 5 to swing it forward, (see Fig. 4,) and its upper side then acts to depress the fork-tail and additionally acts to prevent 50 any possible tilting of the fork should any filling end be present. At the same time it maintains the fork-tail down in position to be certainly engaged by the hook-shoulder as the main vibrator W moves outward, thus 55 insuring the desired coöperation and consequent full outward movement of the main slide. When so thrown or swung forward, the controller is limited in its movement by the front end 2 of the slot in the hook. This 60 form of fork-controller is very simple. It is accurate in operation and cannot get out of position with relation to the fork-tail, the latter sliding freely in the controller-opening 6, as will be manifest.

65 My invention is not restricted to the pre-

cise construction and arrangement herein shown and described, as the same may be modified or varied in different particulars by those skilled in the art without departing from the spirit and scope of my invention. 70

Having fully described my invention, what I claim as new, and desire to secure by Letters Patent, is—

1. In filling-detecting mechanism for 75 looms, in combination, a filling-fork to engage and be moved by intact filling, a vibrator having a hook to coöperate with the fork upon detection of filling absence, and a fork-controller movably mounted on the hook.

2. In filling-detecting mechanism for 80 looms, in combination, a filling-fork to engage and be moved by intact filling, a vibrator having a hook to coöperate with the fork upon detection of filling absence, and a fork-controller fulcrumed on the hook and adapt- 85 ed to limit vibratory movement of the fork.

3. In filling-detecting mechanism for 90 looms, in combination, a filling-fork to engage and be moved by intact filling, a vibrator having a hook to coöperate with the fork 90 upon detection of filling absence, and a loop-like controller pivotally mounted on the hook and coöperating with the tail of the fork to limit vibratory movement thereof.

4. In filling-detecting mechanism for 95 looms, in combination, a filling-fork to engage and be moved by intact filling, and pro- 100 vided with a tail, a vibrator having a shoul- dered hook to engage the fork-tail upon de- 105 tection of filling absence, said hook having a rest portion beyond its shoulder, and a fork- controller movably mounted on the hook and coöperating with the fork-tail, to depress the latter onto the rest portion and maintain it substantially quiescent thereon after filling- 105 induced movement of the fork, during the major portion of the vibrator movement.

5. In filling-detecting mechanism for 110 looms, in combination, a filling-fork to engage and be moved by intact filling, and pro- 115 vided with a tail, a vibrator having a shoul- dered hook to engage the fork-tail upon de- 115 tection of filling absence, said hook having a rest portion beyond its shoulder, and an elon- gated, loop-like controller coöperating with the fork-tail and pivoted on the hook, to de- 120 press the fork-tail onto the rest portion of the hook immediately after filling-induced movement of the fork.

6. In filling-detecting mechanism for 120 looms, in combination, a filling-fork to engage and be moved by intact filling, and pro- 125 vided with a tail, a vibrator having a shoul- dered hook to engage the fork-tail upon de- tection of filling absence, and an elongated, loop-like controller pivoted on the hook and through which the fork-tail loosely passes; 130 said controller being caused to swing rear- wardly and depress the fork-tail upon out- ward movement of the vibrator after the

presence of filling has been detected, return movement of the vibrator acting to swing the controller forward and relieve the fork-tail of pressure.

- 5 7. In a loom, in combination, two filling-detectors normally adapted to detect filling absence on alternate picks, their slides, a vibrator and its hook to coöperate with each detector upon filling absence, to effect outward movement of its slide, filling-replenishing mechanism the operation whereof is directly controlled by such movement of one of the slides, means to effect an initial movement of said slide upon detection of filling absence by the other detector, and a controller movably mounted on the hook of the vibrator adjacent the initially-moved slide, to act upon the corresponding detector and prevent filling-induced movement thereof and also maintain the detector in position to coöperate with the hook.
8. In a loom, in combination, main and auxiliary tilting filling-forks each having a tail, slides on which the forks are mounted, a vibrator and its hook for each fork, filling-replenishing mechanism directly controlled as to its operation by the main fork upon detection of filling absence thereby, means op-

erative by or through detecting action of the auxiliary fork to effect an initial outward movement of the main fork-slide, moving the main fork away from the filling path, and a fork-controller pivotally mounted on the main fork vibrator-hook, to act upon the fork-tail upon initial movement of the main slide and thereby prevent tilting of the main fork while maintaining its tail in position to coöperate with the hook when the outward movement of the slide is completed.

9. In filling-detecting mechanism for looms, in combination, a filling-fork to engage and be moved by intact filling, a vibrator having a hook to coöperate with the fork upon detection of filling absence, and a fork-controller movable with and also relatively to the hook and in sliding engagement with the fork-tail, to govern the vibratory movement of the fork.

In testimony whereof I have signed my name to this specification in the presence of two subscribing witnesses.

ALIDA M. MARCOUX.
